UNITED STATES PATENT OFFICE.

ARCHIBALD McCALLUM, OF HALIFAX, ENGLAND, ASSIGNOR TO JOSEPH WILD & CO., OF NEW YORK CITY.

DESIGN FOR A CARPET-PATTERN.

Specification forming part of Design No. 5,420, dated December 12, 1871.

To all whom it may concern:

Be it known that I, ARCHIBALD McCALLUM, of Halifax, in the county of York, England, have invented a new and original Design for a Carpet, of which the following is a specification:

In the drawing, n o p represent the series of figures.

The nature of my design is fully represented in the accompanying photographic illustration, to which reference is made.

I claim as my invention—

The design for a carpet, as shown.

ARCHIBALD McCALLUM.
